UNITED STATES PATENT OFFICE.

WILLIAM J. MONTGOMERY, OF COLUMBUS, OHIO, ASSIGNOR TO THE JEFFREY MANUFACTURING COMPANY, OF COLUMBUS, OHIO, A CORPORATION OF OHIO.

VENTILATING APPARATUS.

Application filed October 28, 1922. Serial No. 597,669.

The present invention relates to certain new and useful improvements in ventilating apparatus adapted to induce a current of air through the chambers and passages of a mine.

The ventilation of mines is usually effected by currents of air flowing into the mine at one opening, circulating through the passages of the mine, and escaping at another opening. These currents of air are commonly produced by power actuated devices placed outside the mine and connected with its chambers by a suitable air course. To guard against the interruption of ventilating service due to break down of the air propelling devices, such apparatus is installed in duplicate, one unit being held in reserve while the other is in active service, and valves are arranged to direct the flow of air to the preferred air propelling device.

The especial object of this invention is to provide an improved arrangement of valves whereby the flow of air will be automatically switched from the idle to the active air propeller when power is applied to one and cut off from the other.

The means by which I attain this object are fully set forth in the following specification, and illustrated in the accompanying drawings of which—

Fig. 1, is a plan view of a two unit air propeller installation arranged to draw the air from the air shaft of a mine, equipped with the devices of my invention.

Fig. 2, is a sectional view taken along the line II—II of Fig. 1.

Fig. 3, is a view similar to Fig. 1 showing the air propellers arranged to force the air into the air shaft of the mine.

Like numerals refer to similar parts in the several figures.

In the drawings the numeral 1 refers to an air shaft which communicates with the passages of a mine, and the numeral 2 refers to a housing enclosing the mouth of that air shaft. Positioned within the housing 2, at opposite sides of the mouth of the shaft 1, are two air propelling devices which may be of any preferred construction adapted to induce a flow of air through the shaft 1. For purposes of illustration I have shown, in Figs. 1 and 2 of the drawings, two exhaust fans 3 and 4, each of which comprises a spiral casing 5 having a chimney 6 projecting through the roof of the housing 2,

Mounted within the casings 5 are fan wheels 7 each supported upon a suitable shaft 8 journaled in the bearings 9 in the manner well understood in the art. In the sides of each of the casings 5 are circular apertures 10 through which air may be drawn by the fan wheel 7 from the housing 2 to be discharged through the chimney 6. To insure against interruption of the ventilating service of the mine, the fan 3 is arranged to be actuated by an electric motor 11 connected with any convenient source of electric power supply, while the fan 4 is directly connected with a steam engine 12 supplied with steam from any convenient source.

It will be observed that the housing 2 for the oppositely disposed air current inducing means communicates with the shaft 1, forming, as here shown, horizontally disposed conduits, each leading from the vertical shaft 1 to its particular air propeller. The specific arrangement of the housing and conduits and air shaft may, of course, be varied to meet conditions, and, obviously, more than two propeller units could be used if desired, the essential thing being that the connection between propeller units and the shaft to be ventilated be such that the valve mechanisms or cut off means of all inactive propeller units will be closed by the action of the active unit.

If one of these fans, as for example the fan 3, should be active, and the other fan 4 idle, air would tend to flow from the outside atmosphere through the chimney and casing of the fan 4 into the housing 2, materially weakening, if not entirely interrupting, the flow of air from the shaft 1. To prevent such short circuiting of the air system of the mine, valves 13 and 14 are arranged between the mouth of the shaft and the fans 3 and 4 respectively. These valves are hinged to swing outwardly from the mouth of the shaft, and are so disposed that a draught induced by the fan 3 will open the valve 13 and close the valve 14, while a draught induced by the fan 4 will open the valve 14 and close the valve 13. By this arrangement when one fan is started and the other fan stopped, the flow of air from the air shaft 1 is automatically switched from the idle to the active fan.

In Fig. 3, I have illustrated a modified arrangement wherein the fans are adapted to draw air from the external atmosphere and

blow it into the shaft 1. In such case a single valve 15 is provided, hinged at substantially the central plane of the shaft 1 in such manner that the draught induced by the fan 3^a will swing the valve 15 towards the fan 4^a to prevent the escape of air through its casing, and the draught induced by the fan 4^a will swing the valve 15 in the opposite direction towards the fan 3^a to shut off the escape of air through its casing.

What I claim is:—

1. In a stationary ventilating system, the combination of a plurality of alternately independently operable means individually capable of inducing an air current in a vertical air passage and arranged on opposite sides of said vertical passage, and means responsive to an air current induced by any one of said current inducing means to prevent flow of air through another of the air inducing means.
2. In a stationary ventilating system, the combination of a substantially horizontal housing communicating between its ends with a vertical air passage, alternately independently operable means on either side of said vertical air passage individually capable of inducing an air current in the air passage and said housing, and valve mechanism arranged upon opposite sides of said vertical passage and responsive to the action of either one of said means to close communication between the inactive air current inducing means and the vertical air passage.
3. In an apparatus of the class described, a housing communicating between its ends with a ventilator shaft, a pivoted flap in said housing at either side of said shaft and adapted to assume a transverse position relative to said housing to close communica-

tion between respective ends of the housing and the shaft, and to swing back against the housing wall to allow such communication, said flaps being swingable away from said shaft, said housing having a divergent wall at either side of said shaft, the points of divergence of said walls being overlapped by the free ends of said flaps when the latter are in swing-back position, and alternatively operable draft creating means at either end of said housing.

4. In a stationary ventilating system, the combination of a housing communicating between its ends with an air passage, alternately independently operable air current inducing means in said housing on opposite sides of said air passage and individually capable of inducing an air current in the air passage, and means responsive to an air current induced by either of said air current inducing means to prevent flow of air through the opposite air inducing means.

5. In a stationary ventilating system, the combination of a substantially horizontal housing communicating between its ends with a vertical air passage, alternately independently operable means on either side of said vertical air passage individually capable of inducing an air current in the air passage and said housing, and valve mechanism interposed between said air current inducing means and responsive to the action of either one of said means to close communication between the inactive air current inducing means and the vertical air passage.

In testimony whereof, I affix my signature.

WILLIAM J. MONTGOMERY.
